CANDLE HOLDER FOR USE ON BIRTHDAY CAKES OR THE LIKE

Ernest B. Thomas, Chicago, Ill.

Application April 7, 1954, Serial No. 29,902

Term of patent 3½ years

(Cl. D48—2)

FIG.1.

FIG.2.

FIG.3.

Fig. 1 is a front elevational view of a candle holder for use on birthday cakes, showing my new design;

Fig. 2 is a side elevational view thereof; and

Fig. 3 is a top plan view.

The dotted lines shown in the drawing are for illustrative purposes only.

I claim:

The ornamental design for a candle holder for use on birthday cakes or the like, substantially as shown and described.
